(57) CLAIM

The ornamental design for a condiment dispensing carousel, as shown and described.

DESCRIPTION

FIG. 1 is a perspective view of the condiment dispensing carousel showing my new design;

FIG. 2 is a top plan view thereof;

FIG. 3 is a front elevation view thereof;

FIG. 4 is a perspective view of the carousel shown without the dispensers for clarity of illustration;

FIG. 5 is a perspective view of the dispenser shown separately for clarity of illustration;

FIG. 6 is a top plan view of FIG. 5;

FIG. 7 is a front elevation of FIG. 5;

FIG. 8 is a perspective view of FIG. 5 in an open position; and,

FIG. 9 is a front elevation view of an alternate embodiment of FIG. 1, the difference being that there are the dispensing carousels are stacked on top of each other.

The undisclosed bottom views of the carousel and dispensers are unadorned.
